UNITED STATES PATENT OFFICE.

HENRY JANSSEN, OF WYOMISSING, PENNSYLVANIA, ASSIGNEE TO TEXTILE MACHINE WORKS, INCORPORATED, OF WYOMISSING, PENNSYLVANIA.

CHANGE-GEARING FOR BRAIDING-MACHINES.

No. 873,698.

Specification of Letters Patent.

Patented Dec. 10, 1907.

Application filed December 4, 1905. Serial No. 290,108.

To all whom it may concern:

Be it known that I, HENRY JANSSEN, a citizen of the United States, and a resident of Wyomissing, county of Berks, and State of Pennsylvania, have invented certain new and useful Improvements in Change-Gearing for Braiding-Machines, of which the following is a specification.

My invention relates to certain improvements in braiding machines whereby the changes which are required to be made in the gearing in order to make desired changes in the product, may be effected with greater ease and in shorter time than heretofore, and the construction of the machine at the same time be simplified.

The changes commonly desired merely require that the number of carriers employed shall be varied by means of different terminal gears for reversing the course of the carriers;—for instance a five-horn terminal gear, that is one having a carrier driving-head provided with five carrier-engaging notches, as commonly employed in making “plain” braid, a six-horn for “diamond” braid, and a three-horn for “open-work”; and the speed of rotation of these different terminal gears must be correspondingly varied by providing a proper proportion of teeth in the meshing terminal and adjacent gears.

The main object of my invention is to enable these variations in the machine to be easily and simply effected, and it consists in providing for changing the terminal gears only as desired without requiring any changing of the adjacent meshing gear, or of the location of the terminal stud to vary the distances between the gear centers.

The invention is fully described in connection with the accompanying drawings and the novel features are clearly pointed out in the claims.

Figure 1 is a partial sectional elevation of a braiding machine embodying all the features of my invention; a terminal three-horn gear and the adjacent four-horn gear only being shown in operative position. Fig. 2 is a similar view to Fig. 1 showing the terminal-gear stud removed and a five-horn (or six-horn) gear put in place of the three-horn and ready to be secured by replacing the stud in its

original position. Figs. 3, 4, and 5 are plan views respectively of the three-horn, five-horn and six-horn gears which are interchangeably mounted upon the terminal stud. 55

A and B represent respectively the usual bottom and top plates of a braiding machine, between which the series of “horn-gears” for operating the bobbin-carriers are mounted upon a corresponding series of vertical 60 studs or bolts fixed to the bottom plate A. Only the terminal-gear stud 2, upon which the different terminal-gears are interchangeably mounted, and the adjacent stud 3 upon which the end one of the usual four-horn 65 gears is mounted, are illustrated, these only being necessary to the showing of my invention.

The four-horn gear which is mounted upon the stud 3 is shown in Fig. 1 as a compound 70 gear, differing from the other ordinary four-horn gears only in being provided with an additional toothed wheel 5, located in a plane above the drive-gear 6, which latter is the same as on all the four-horn gears; this additional toothed wheel being added in this case only to provide for the change to the three-horn gear shown on the terminal stud 2 in Fig. 1, and being an unused idler when either the five-horn gear (Fig. 4) or six-horn gear 80 (Fig. 5) are mounted on said terminal stud.

It being necessary that the different terminal gears which are interchangeably mounted on the terminal stud 2, be rotated at different speeds corresponding to the different number of carrier-engaging notches or horns with which they are provided, the change from one terminal gear to another has heretofore involved the changing of the location of the terminal stud 2 relative to the adjacent 90 stud 3, and the changing of the horn-gears upon both of said studs, so as to secure the required speed of rotation of the particular terminal-gear employed. In my improved construction I provide for maintaining the 95 terminal stud 2 in a fixed location, and at the same time for avoiding any change of the horn-gear on the adjacent stud 3; the changing of the terminal gears only being required, and this change being effected in a simple, expeditious and satisfactory manner. To accomplish this I permanently space the termi-

nal stud 2 from the adjacent stud 3 a distance somewhat greater than is ordinarily required for the proper speeding of the five-horn gear and somewhat less than is required for the six-horn gear. For instance, the four-horn drive-gear 6 having twenty-four teeth (three inches pitch circle), the five-horn gear 7 will require thirty teeth and the six-horn gear 8 thirty-six teeth, requiring pitch diameters of three and three fourth inches and four and one half inches respectively; and instead of providing for changing the location of the stud 2 to one or other of the different spacings from stud 3 required by these different pitch circles, I adopt a fixed spacing based on a compromise pitch-circle of four and one quarter inches for both the five-horn and six-horn terminal gears, or three and five eighths inches spacing between studs 2 and 3; and instead of providing the different terminal gears with normally shaped teeth (thirty-four to each gear) I make them both "bastard-gears" of thirty teeth and thirty-six teeth respectively, as indicated in Figs. 4 and 5, in which it will be seen that the teeth of the five-horn gear are abnormally pointed and wide at the base, while those of the six-horn gear are abnormally blunt and narrow at the base, both forms of teeth however being adapted to mesh properly with the normally toothed four-horn drive-gear 6. Thus either the five-horn or six-horn terminal gear may be employed upon the fixedly spaced terminal-stud 2, and each will be driven by the adjacent four-horn gear at the proper speed. When only three horns or notches are wanted in the terminal gear, the additional toothed-wheel 5 on the adjacent four-horn gear (see Fig. 1) comes into service, a compound three-horn terminal gear being preferably employed as shown, in which the lower gear 9 is turned idly by the adjacent drive-gear 6 to transmit movement to an adjacent gear (not shown) on the opposite side of the terminal stud, while the three-horn terminal gear is driven by said additional toothed-wheel 5 of the four-horn gear 6. The required relative rotation of said gear 6 and of the three-horn terminal is obviously secured by making the relative number of teeth in the additional toothed-wheel 5 and in the upper gear 10 of the three-horn terminal, as four to three; and where the idler 9 is not employed, these teeth may be made of normal shape. But when such idler is employed, as is preferable, it is necessary that the difference between the two pitch-circles of each compound gear shall be the same in order that all may properly mesh and I secure this result by making both the upper gears (5 and 10) "bastard-gears", the additional toothed-wheel 5, in the specific construction described and illustrated, hav-

ing a pitch-circle of four and fourteen one hundredths inches with thirty-two teeth, and 65 the meshing gear 10 of the three-horn terminal a pitch circle of three and eleven one hundredths inches with twenty-four teeth, and each varying one and fourteen one hundredths inches from the pitch circle of the 70 corresponding lower gear.

To provide for conveniently changing the terminal gears as desired I employ a terminal-stud 2 having a body portion 11 of uniform diameter throughout, a reduced lower end 75 12 secured in a fixed perforation in the bottom plate A by a removable nut 13, and a reduced upper end upon which the "quoit" 14 of the top plate B is secured; and a removable collar 15 seated upon the bottom 80 plate and upon which the rotary horn-gears are mounted. In order to substitute another of the terminal gears for one in service, the nut 13 is merely removed, the stud 2 (with quoit 14 and needle post 16, if employed, attached) raised through the terminal gear and the collar 15, said gear removed laterally and the different one substituted, and the stud returned to its original position and secured as before. 90

The considerable saving in time and labor involved in making a change, as well as the simplicity and economy of my improved construction will be readily understood.

The preferred construction specifically described and shown may readily be modified.

What I claim is:—

1. A braiding machine comprising a series of gear studs with meshing four-horn gears thereon an end one of which is a compound gear, and a terminal gear stud removably secured at a distance from said end four-horn stud which is intermediate between the normal distance for a five-horn and the normal distance for a six-horn gear, whereby different terminal horn-gears as described may be interchangeably mounted upon said terminal stud in required relation to said end four-horn gear substantially as set forth. 100

2. In a braiding machine having a series of gear studs with meshing four-horn gears thereon, and a terminal gear stud removably secured at a distance from the adjacent stud which is intermediate between the normal distance for a five-horn and the normal distance for a six-horn gear, a terminal gear for said terminal stud having bastard teeth adapted to mesh with the adjacent four-horn gear and the number of such teeth being properly proportioned to its carrier engaging 115 120 horns, substantially as and for the purpose set forth.

3. In a braiding machine having a series of gear studs with meshing four-horn gears thereon, and a terminal gear stud removably secured at a distance from the adjacent stud 125

which is intermediate between the normal distance for a five-horn and the normal distance for a six-horn gear, an idler gear and a terminal horn-gear jointly mounted upon 5 said terminal stud and meshing with said adjacent compound gear substantially as set forth:

In testimony whereof, I affix my signature, in the presence of two witnesses.

HENRY JANSSEN.
